Office Action from Design U.S. Appl. No. 29/451,766, dated Aug. 29, 2013.

Primary Examiner — Phillip S Hyder(74) *Attorney, Agent, or Firm* — Wolf, Greenfield & Sacks, P.C.; Randy J. Pritzker(57) **CLAIM**

The ornamental design for an intermediate adapter for a camera, as shown and described.

DESCRIPTION

FIG. 1 is a perspective view of an embodiment of an intermediate adapter for a camera showing my new design;

FIG. 2 is a rear elevational view thereof;

FIG. 3 is a top plan view thereof;

FIG. 4 is a bottom plan view thereof;

FIG. 5 is a right side elevational view thereof; and,

FIG. 6 is a left side elevational view thereof.

The features shown in broken lines in the drawings depict environmental subject matter only and form no part of the claimed design. The dot-dashed lines denote the boundary of the claim, and form no part of the claimed design.

1 Claim, 6 Drawing Sheets---
